CRUCIBLE COMPANY, OF JERSEY CITY, NEW JERSEY, A CORPORATION OF NEW
JERSEY

PENCIL

Application filed June 24, 1930. Serial No. 463,420.

The present invention relates to an improvement in pencils and more particularly in eraser holding attachments for "lead" pencils sheathed in wood or equivalent material.

The general object of the invention is to provide a device of this character which will be more slight in appearance, cheaper to manufacture and more readily attachable to pencils than those heretofore proposed or in use. A more specific object of the invention resides in the provision of a superior eraser attachment or holder molded from a synthetic resin or phenolic condensation product.

Other objects and advantages of the invention will appear from the following detailed description of one preferred form thereof, reference being had to the accompanying drawings wherein: Fig. 1 is a side elevation of a pencil having an eraser attached thereto by means in accordance with the present invention. Fig. 2 is a detailed view partly in section of the upper portion of Fig. 1. Fig. 3 is a plan view looking down from above in Fig. 2. Fig. 4 is a section taken on the line 4—4 of Fig. 2 looking in the direction of the arrows.

There is shown at 1 a pencil sheath of wood or similar material surrounding a "lead" 2. This sheath is of hexagonal form and is provided with a portion 3 at one end thereof which is reduced in size and is likewise of generally hexagonal shape, for the purposes hereinafter indicated. The attachment 4 for holding the eraser on the pencil is composed of a synthetic resin or molded phenolic material, such as bakelite, and comprises a tubular portion 5 for engagement with the pencil and an enlarged tubular portion 6 for holding the eraser. The tubular portion 5 is interiorly threaded at 7, the threads being adapted to engage the corners 8 of the reduced portion 3 of the pencil, forming depressions 9 in these corners as the attachment is screwed on to the pencil. The threads 7 are made of the material of which the attachment is composed and form an integral part thereof. Any necessity for the provision of cooper-

ating threads on the pencil is avoided, save as the threads in the attachment form grooves in the pencil when it is initially attached to the latter. The attachment may thus be placed on the pencil or removed at will. Between portions 5 and 6, there is provided a transverse partition 10. The reduction of the cross-section on the end of the pencil forms a shoulder 11 against which the end of tubular portion 5 seats or abuts, the height of this portion being somewhat greater than the height of the reduced portion of the pencil to avoid abutment of the end of the pencil against the partition, and consequent possibility of an imperfect fit at the shoulder. Externally, portion 5 is circular in cross-section and tapers slightly towards shoulder 11. The portion 6 has a circular interior and polygonal exterior, the latter so that it may be gripped when the attachment is to be screwed on to the pencil. Within portion 6 the eraser 12 is seated, and may be cemented therein.

While I have described my invention with reference to the specific embodiment illustrated, I do not wish to be limited save by the scope of the appended claims.

I claim:

1. In combination with a wooden sheath having an end portion reduced in size to form a shoulder spaced inwardly from the extremity of said end portion, a unitary attachment of synthetic resinous material comprising a reduced tubular portion internally screw threaded with the bore formed by the edges of the thread of less diameter than the diameter of the reduced portion whereby threads will be formed on the reduced portion of the sheath when the attachment is applied thereto, said attachment having a second, relatively enlarged, tubular portion to hold an eraser and a partition to separate said tubular portions spaced from the free edge of the threaded portion a distance greater than the length of said reduced end portion of the wooden sheath, the free edge of the threaded tubular portion engaging said shoulder of the sheath to stop movement of the attachment on the sheath before engagement of said pencil extremity.

with the partition, the enlarged eraser receiving tubular portion being exteriorly provided with elongated flattened surfaces substantially co-extensive therewith.

5 2. In combination with a wooden sheath having an end portion reduced in size to form a shoulder spaced inwardly from the extremity of said end portion, a unitary attachment comprising a tubular portion internally screw threaded with the bore formed by the edges of the thread of less diameter than the diameter of the reduced portion whereby threads will be formed on the reduced portion of the sheath when the 10 attachment is forcibly applied thereto, said attachment having a second relatively larger tubular portion to hold an eraser, the free edge of the threaded tubular portion engaging said shoulder of the sheath to stop movement of the attachment on the sheath.

HORACE B. VAN DORN.
